UNITED STATES PATENT OFFICE.

HERLIN M. APPELGATE, OF BROOKLYN, NEW YORK, ASSIGNOR OF ONE-HALF TO
IRVING WARNER, OF NEW YORK, N. Y.

ELECTRIC TIMER.

Application filed September 27, 1922. Serial No. 590,865.

To all whom it may concern:

Be it known that I, HERLIN M. APPEL-GATE, a citizen of the United States, and a resident of New York, borough of Brooklyn, in the county of Kings and State of New York, have invented certain new and useful Improvements in an Electric Timer, of which the following is a full, clear, and exact specification.

10 This invention relates to a class of devices adapted to be used in conjunction with the ignition system especially of internal combustion engines.

My invention has for its object primarily 15 to provide a timer designed to be employed in the electric system when provided for igniting the gaseous fuel products of an internal combustion engine so that the intermittent sparking of the electric plugs 20 of the engine will be effectually accomplished by the device being operated by the crank shaft of the engine so that the delivery of the electric current to the plugs will be properly timed relative to determined 25 positions of the piston of the engine during its reciprocation. The invention also contemplates an improved form of the device disclosed in my pending application for a patent, serially numbered 506,978 30 filed October 11, 1921, by being composed of parts so formed and arranged that the device may be made at a minimum cost as well as capable of being readily mounted on the engine shaft for operation in a manner 35 whereby a uniform sparking of the plug will be accomplished at determined intervals through the provision of three-point wiping contacts between conductive surfaces for intermittently closing the circuit, instead of the usual provision for making only one-point contacts which frequently collect oil or grease that cause 40 unsteady sparking of the plug with consequent uneven firing of the fuel products owing to arcing of the current.

45 A further object of the invention is to provide an electric timer of a simple, efficient and durable construction which may be made in any suitable size and shape.

50 With these and other objects in view, the invention will be hereinafter more fully explained with reference to the accompanying drawing forming a part of this specification in which similar characters of reference indicate corresponding parts in all the

views, and will then be pointed out in the claims at the end of the description.

In the drawing, Figure 1 is a longitudinal vertical section, partly fragmentary and partly in detail, taken on the line 1—1 of Fig. 2.

Fig. 2. is a detail sectional view, partly fragmentary, taken on the line 2—2 of Fig. 1, and

Fig. 3 is a detail sectional view taken on the line 3—3 of Fig. 1.

The device or timer has a casing or cap 10 which may be of any suitable shape and size, though the form of the casing shown is somewhat cup-shaped to provide a curved 70 or tapered plate or wall, as 11, with a straight annular flange or wall as 12, on its edge extending from the concaved face of the plate. This casing is of a size so that when arranged over the end of the cam 75 shaft, as 13, of an internal combustion engine with the shaft extending into the center of the concavity of the casing, as illustrated, the annular flange 12 of the casing will be spaced some distance from 80 the shaft. Protruding inwardly of the casing from the flange 12 is an annular rail or rib 14 of fibre or other appropriate insulating material. The insulating rail is preferably substantially rectangular, in cross-section, as well as being of a width and of a diameter so that its inner periphery is also spaced from the conductive shaft 13. The rail 14 is also arranged on the flange 12 of the casing 10 so that its inner face and both 85 side faces are exposed, and in equidistant spaced parts of the annular insulating rail are embedded correspondingly electric contacts or conductive blocks, as 15. While any desired number of these conductive 90 blocks may be used, in the form of the device shown there are four of the blocks, and each block is substantially rectangular. The blocks are of sizes as well as being curved so that their inner faces and side 95 edges are flush with the side faces and inner periphery of the rail. The conductive blocks 15 are adapted to be interposed in an electric circuit by appropriate binding posts, as 16, each of which leads from each 100 of the blocks through the insulating rail 14 and through holes in casing so that they extend from the flange 12 of the casing for being connected to the conductive wires of a source of electrical energy, the wires also 110

leading to the spark plugs of one or more cylinders of an internal combustion engine, not shown. These parts of the device may be of well known forms.

On part of the flange 12 of the casing 10 is a clamp, as 17, adapted to detachably fasten the casing with the rail 14 and conductive blocks 15 to a rod, as 18, which is adjustable for adjusting the casing, rail conductive blocks circumferentially of the cam shaft 13 when the device is in use. The clamp 17 is preferably composed of two spaced spring prongs 19 and 20 having one of their ends secured, at 21, to the casing 15 so that their other ends protrude laterally from the casing. The second end parts of the prongs are oppositely curved, as at 22, for removably receiving one end of the rod 18 to support the casing in a depending position for adjustment common to the employment of this type of device for advancing and retarding the sparking of electric plugs, and the rod is releasably clamped in the prongs by a set screw 23 which is rotatable in registered threaded holes provided in the central parts of the prongs.

In order to cause the circuit in which the device is interposed to be intermittently closed for sparking the plugs at intervals 30 a conductive rotary member or metal roller, as 24, is provided. This conductive roller is peripherally grooved, as at 25, to provide on the edges of the roller two annular flanges 26 and 27, and the groove is of a 35 width slightly less than the widths of the conductive blocks 15 as well as being slightly less than the width of the insulating rail 14. The roller is divided lengthwise centrally of the bottom of the groove 25 into 40 halves, as 28 and 29, and in the inner face of the half 29 is a socket 30, while on a corresponding part of the inner face of the half 28 is a protruding pin or lug 31 which is normally seated removably in the socket 45 of the half 29 to cause the halves to revolve in unison when the roller is revolved. The roller is rotatably mounted on a conductive stud 31 having its ends held to the ends of 50 two parallel spaced flat conductive bars 32 and 33 so that the roller is rotatable between these bars, and the roller is of a width so that the outer faces of its halves are spaced from the bars 32 and 33 for allowing the halves to be spread apart on the stud sufficient distance whereby the pin 31 may be 55 removed from the socket 30 and contacted with the inner face of the socketed half 29 for holding the halves of the roller in spaced relation, as will be hereinafter more fully explained. Between the second ends of the 60 bars 32 and 33 is a fixed rod 34, and between the central parts of the bars is held another conductive rod 35. On the end portions of both of the rods 34 and 35 are held 65 the ends of flat metal strip springs, as 36

and 37, having on their other ends partially circular enlarged flat portions, as 38 and 39, and in the central parts of these enlarged portions are registered holes through which pass the end portions of the stud 32 of the 70 roller 24. The springs 36 and 37 are thereby disposed between the bars 32 and 33 and the outer faces of the roller, and these springs are tensioned to yieldingly force the halves of the rollers normally toward each other. On the central part of the rod 35 is 75 rotatably held the apertured ends of two spaced lugs 42 and 43 of a conductive bracket, as 43, and the other ends of the lugs are bridged, as at 44. This bracket is, 80 therefore, substantially U-shaped, and the bridging member 44 of the bracket is held to the central part of the exterior of a conductive sleeve 45 adapted to be suitably fastened, as at 46, to the shaft 13 of the engine. The bracket 43 is disposed relative to the sleeve 45 on an incline toward the insulating rail 14, and the spaced bars 32 and 33 are thereby disposed tangentially 85 crosswise of the sleeve so that the conductive 90 roller 24 will be properly positioned for traveling on the rail. The roller 24 is yieldingly held in revolvable engagement with the rail by the tension of one or two springs, as 47 and 48, having one of their 95 ends held to the rod 34 of the bars 32 and 33, while the other ends of the spring are fastened, at 49 and 50, to part of the sleeve 45 so that the action of the springs normally 100 serve to force one of the ends of the bars 32 and 33 toward the sleeve 45 with the other ends of the bars being yieldingly forced toward the rail 14 which in turn will yieldingly hold the roller 24 in 105 straddle arrangement on the rail so that the bottom of the groove 25 with its side walls or flanges 26 and 27 will make a wiping contact with the inner faces and side edges of the conductive blocks 15, in order that liability of interruptions 110 occurring in the circuit from oil or grease collecting on the blocks will be avoided as is incident to the use of timers of this class.

As the annular rail 14 must be of a given diameter so that the conductive contact 115 blocks 15 will be spaced at determined intervals the space between the rail and shaft 13 is limited, and to permit the roller 24 to be readily arranged on the rail the socket 30 and pin 31 are provided on the halves 28 and 29 of the roller. As hereinbefore explained, this is accomplished by spacing the halves of the roller so that the pin 31 is removed from the socket 30, and by partially rotating one of the halves of the roller the 120 end of the pin will engage the inner face of the socketed half. The roller may then be 125 easily disposed in straddling position on the inner face of the rail 14, also as above explained, so that with the driving of the 130

shaft 13 the sleeve 45, bracket 43, bars 32 and 33 will be revolvably swung to cause the conductive roller to close the electric circuit in the well known manner, through the conductive blocks 15 and through the binding posts 16 to the plugs of an internal combustion engine for intermittently sparking the plugs, and I have found that the provision of the straight bars 32 and 33, instead 10 of using curved bars, enabled the device to be manufactured at a very reasonable cost.

In the foregoing description, I have embodied the preferred form of my invention, but I do not wish to be understood as limiting myself thereto, as I am aware that modifications may be made therein without departing from the principle or sacrificing any of the advantages of this invention, therefore, I reserve to myself the right to make 20 such changes as fairly fall within the scope thereof.

Having thus described my invention, I claim as new and desire to secure by Letters Patent:—

25 1. In a timer as characterized, the combination with an insulating annular rail having spaced embedded conductive blocks, each with three exposed faces and each block adapted to be interposed in an electric circuit, of a peripherally grooved conductive roller divided lengthwise into halves, one having a socket and the other having a protruding pin for removable insertion into the socket.

30 2. In a timer as characterized, the combination with an insulating annular rail having four spaced embedded conductive blocks, each with three exposed faces and each block adapted to be interposed in an electric circuit, of a peripherally grooved conductive roller divided lengthwise into halves, one having a socket and the other having a protruding pin for removable insertion into the socket, and spring controlled 35 conductive means revolvably carrying the roller and adapted to be conductively fastened on the conductive shaft.

35 3. In a timer as characterized, the combination with an insulating annular rail having four spaced embedded conductive blocks, each with three exposed faces and each block adapted to be interposed in an electric circuit, of clamping prongs for detachably engaging a movable rod whereby the rail and blocks may be supported for rotatable adjustment surrounding a conductive shaft by adjusting the rod, a peripherally grooved conductive roller divided lengthwise into halves, one having a socket and the other having a protruding pin for removable insertion into the socket, and spring controlled conductive means revolvably carrying the roller and adapted to be conductively fastened on the conductive shaft.

40 4. In a timer as characterized, the com-

bination with an insulating annular rail having four spaced embedded conductive blocks, each with three exposed faces and each block adapted to be interposed in an electric circuit, of a peripherally grooved 70 conductive roller divided lengthwise into halves, one having a socket and the other having a protruding pin for removable insertion into the socket, a conductive sleeve adapted to be fastened on the conductive shaft of a combustion engine, and two conductive straight bars yieldingly bracketed to the sleeve tangentially with relation thereto and the bars rotatably carrying said roller.

5. In a timer as characterized, the combination with an insulating annular rail having four spaced embedded conductive blocks, each with three exposed faces and each block adapted to be interposed in an electric circuit, of clamping prongs for detachably engaging a movable rod whereby the rail and blocks may be supported for rotatable adjustment surrounding a conductive shaft by adjusting the rod, a peripherally grooved conductive roller divided lengthwise into halves, one having a socket and the other having a protruding pin for removable insertion into the socket, a conductive sleeve adapted to be fastened on the conductive shaft of a combustion engine, and two conductive straight bars yieldingly bracketed to the sleeve tangentially with relation thereto and the bars rotatably carrying said roller.

6. In a timer as characterized, in combination, a casing having on its interior an insulating annular rail with four spaced embedded conductive blocks, each having three exposed faces and each block adapted to be interposed in an electric circuit, and a peripherally grooved conductive roller divided lengthwise into halves, one having a socket and the other having a protruding pin for removable insertion into the socket.

7. In a timer as characterized, in combination, a casing having on its interior an insulating annular rail with four spaced embedded conductive blocks, each having three exposed faces and each block adapted to be interposed in an electric circuit, clamping prongs for detachably engaging a movable rod whereby the rail and blocks may be supported for rotatable adjustment surrounding a conductive shaft by adjusting the rod, and a peripherally grooved conductive roller divided lengthwise into halves, one having a socket and the other having a protruding pin for removable insertion into the socket.

8. In a timer as characterized, in combination, a casing having on its interior an insulating annular rail with four spaced embedded conductive blocks, each having three exposed faces and each block adapted to be interposed in an electric circuit, clamp-

ing prongs for detachably engaging a movable rod whereby the rail and blocks may be supported for rotatable adjustment surrounding a conductive shaft by adjusting 10
5 the rod, a peripherally grooved conductive roller divided lengthwise into halves, one having a socket and the other having a protruding pin for removable insertion into the socket, and spring controlled conductive

means revolvably carrying the roller and 10
adapted to be conductively fastened on the conductive shaft.

This specification signed and witnessed
this 26th day of September, A. D. 1922.
